UNITED STATES PATENT OFFICE.

PETER HARVEY FLYNN, OF NEW YORK, N. Y.

BRIDLE.

SPECIFICATION forming part of Letters Patent No. 678,388, dated July 16, 1901.

Application filed September 23, 1899. Serial No. 731,466. (No model.)

To all whom it may concern:

Be it known that I, PETER HARVEY FLYNN, a citizen of the United States, and a resident of New York, in the county and State of New York, have invented a certain new and useful Appliance for Controlling Fractious Horses, of which the following is a specification.

My invention relates to an appliance for use in connection with a bit for controlling fractious and unruly horses; and it has for its object the provision of an appliance of this character which is simple in construction, inexpensive to manufacture, and which operates efficiently in practical use.

To attain the desired end, this my invention consists in certain novel features of construction and combination of parts, which will be hereinafter more fully described and claimed.

In order to enable my invention to be fully understood, I will proceed to explain the same by reference to the drawings which accompany and form a part of this specification, and in which—

Figure 1 represents a plan view of my improved appliance as applied to a bridle-bit. Fig. 2 is a plan view of the same in operation. Fig. 3 is a side elevation of the bit and appliance.

Like letters of reference indicate like parts in all the views.

I have found it desirable to make an appliance whereby lateral pressure may be applied to the cheeks of an unruly or fractious horse, whereby the horse may be caused to open its mouth and release the bit, and I have therefore constructed according to my invention an appliance of the class described embodying the preferred construction of parts and their mutual relationship, combination, arrangement, and organization in a composite body or structure adapted to perform the function stated in a more certain and perfect manner than heretofore, as hereinafter described.

Referring now more particularly to the drawings, A denotes a snaffle or joint bit of ordinary construction, which may be provided with rings A' for reins, and cheek-pieces A². I provide means whereby lateral pressure as regards the bit may be applied at or near the ends of the same, by which the cheeks of the

horse are squeezed and great pressure brought against the nerves of the gums when the reins are pulled with extraordinary force, which means consists of a segmental resilient nose-band B, formed of flat spring metal and connected at its ends to elongated link-shaped rigid or non-resilient jaw-pieces B', mounted upon the ends of the bit. These jaw-pieces B' are adapted to bear upon opposite sides of the upper jaw of the horse when moved inward to squeeze the same and press upon the gums to cause the horse to release his hold upon the bit and, to adapt them to perform this function to the best advantage, are constructed in a peculiar manner. As is well known, the natural tendency of straight jaw-pieces when used in connection with a jointed or snaffle bit is, when the bit is pulled and the ends of the bit-sections are drawn rearwardly, to tilt or incline, thus rendering their clamping action on the jaw comparatively weak and ineffective. To overcome this objection, I curve the inner ends of the jaw-pieces outwardly, so that each normally assumes a position at an acute angle to the normal position of the bit-sections. When the bit-sections are drawn upon, however, to operate the jaw-pieces, said jaw-pieces are forced inwardly or toward each other and caused to assume a position at right angles to the normal position of the bit-sections, whereby the knobs or projections b' are brought to bear squarely upon the jaw instead of taking an inclined position, and consequently exert a much more powerful clamping action than would be the case if straight jaw-pieces were employed.

To adapt the jaw-pieces for exerting a more powerful pressure than otherwise and to provide for the ready and convenient application and removal of the appliance, I make said jaw-pieces in the form each of an oblong open link of sufficient length and width to permit of the passage of the rein-ring A' and cheek-pieces A² therethrough and also of a width to provide for an extended bearing upon the jaw and the effective squeezing of the cheek of the animal between the arms thereof. The arms of each jaw-piece are also formed at or about midway of their length with lateral segmental projections or knobs b',

which are adapted when the jaw-pieces are forced inward to bear with great force and to concentrate the pressure at two points upon the gums. It will thus be seen that by making the jaw-pieces of oblong open-link form important advantages are obtained.

The nose-band may be provided, if desired, with an orifice B³, by means of which it may be suspended from the crown of the bridle; but this is not essential, as the use of an overdraw-strap may be dispensed with without affecting the operation of the device.

In operation the nose-band is normally in the position shown in Fig. 1 and is not felt by the horse at all, in consequence of which the horse may be driven with a light hand and controlled by the simple guidance of the finger and thumb. When correction or coercion, however, is necessary, a more severe strain may be applied to the reins, whereupon the great powers of the bridle will be developed sufficient to control the most vicious horse, as by pulling the reins in a backward direction the jaw-pieces B' are forced toward the center or joint of the bit, as shown in Fig. 2, and the projections b' are forced against the cheeks of the horse and press upon the gums of each side, and the pain thus caused forces the horse to open its jaws and release the bit. I prefer to construct the jaw-pieces B' in the form of open oblong links, as these also permit of the same being fastened by a suitable connection to the rear ends of the rings A' to render the appliance inop-

erative when a bridle provided therewith is used upon a gentle horse.

The device may be provided with a leather or other covering to prevent chafing of the horse.

Changes in the form, proportion, and minor details of construction may be made within the scope of the invention without departing from the spirit or sacrificing any of the advantages thereof.

Having thus fully described my invention, what I claim, and desire to secure by Letters Patent, is—

The combination, with a jointed bit, of jaw-pieces slidable upon the bit-sections, said jaw-pieces being provided with projections to bear upon the sides of a horse's jaw and having their inner ends outwardly curved at an acute angle to the normal position of the bit-sections and adapted, when said bit-sections are drawn rearwardly, to assume a position at right angles thereto to bring said projections squarely into contact with the jaw, and a resilient nose-band connecting the outer ends of the jaw-pieces, substantially as set forth.

In testimony of the foregoing specification I do hereby sign the same, in the city of New York, in the county and State of New York, this 22d day of September, A. D. 1899.

PETER HARVEY FLYNN.
